UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

STEM WINDING AND SETTING WATCH.

No. 904,989.

Specification of Letters Patent.

Patented Nov. 24, 1908.

Application filed September 21, 1908. Serial No. 454,021.

To all whom it may concern:

Be it known that I, WILSON E. PORTER, a citizen of the United States, residing at New Haven, in the county of New Haven 5 and State of Connecticut, have invented a new and useful Improvement in Stem-Winding and Stem-Setting Watches; and I do hereby declare the following, when taken in connection with the accompanying drawings and the letters of reference marked thereon, to be full, clear, and exact description of the same, and which said drawings constitute part of this specification, and represent, in—

15 Figure 1 a view in elevation of a watch constructed in accordance with my invention, with the dial removed. Fig. 2 a broken view looking toward the inner face of the front movement-plate. Fig. 3 a broken 20 sectional view on the line $a-b$ of Fig. 1. Fig. 4 a broken view of the front movement-plate to show the radial slot formed for the stud of the movable stem-setting wheel.

25 My invention relates to an improvement in stem-winding and stem-setting watches, the object being to provide a simple, compact and reliable mechanism constructed with particular reference to relieving the dial-work of as much load as possible in its 30 normal operation.

35 With these ends in view my invention consists in the construction and combination of parts as will be hereinafter described and pointed out in the claims.

35 In carrying out my invention as herein shown, I employ a radially movable stem-setting wheel 2 mounted upon a stud 3 passing through a radially arranged slot 4 formed in the front movement-plate 5 and 40 located in line with the longitudinally movable and rotatable winding and setting stem 6 which is mounted in the pendant 7 and furnished at its outer end with a crown 8 in the usual manner. The said wheel 2 bears 45 upon and rides over the outer face of the front movement-plate 5 and is held in place by means of a washer 9 applied to the said stud and bearing upon and riding over the inner face of the said plate 5 as shown in 50 Fig. 3. A spring 10 secured to the inner face of the plate 5 engages with the inner edge of the washer 9 and exerts a constant effort to push the same, and hence the stem-setting wheel 2 outward, whereby the teeth 55 of the wheel 2 are normally demeshed from

the teeth of the dial wheel 11 which is of the ordinary form and arrangement, and in constant mesh with the cannon pinion 12. The dial work of the watch is therefore relieved of the burden of idly operating the stem-setting wheel 2. The spring 10 by pushing outward on the washer 9, as described, keeps the teeth of the stem-setting wheel 2 in constant mesh with the stem-setting pinion 13 which is mounted in the usual manner upon 60 the inner end of the stem 6, the teeth of the wheel 2 being prevented from entering too far into the teeth of the pinion 13 by the abutment of the edge of the washer 9 against the flat inner face of the pinion 13, as shown 65 in Fig. 3, the washer 9 being regulated in diameter accordingly.

70 When it is desired to set the watch the stem 6 is pushed inward by its crown 8, whereby the wheel 2 and washer 9 are 75 forced radially inward against the tension of the spring 10 and the wheel 2 intermeshed with the dial wheel 11 into which the teeth of the wheel 2 are prevented from going too 80 far by the abutment of the stud 3 against the inner end wall of the slot 4. The inward thrust upon the stem 6 is maintained during the setting of the watch. Being relieved, the spring 10 reasserts itself and moves the wheel 2 outward into its normal position in 85 which it is demeshed from the dial wheel 11 as shown in Fig. 1. The spring 10 is not, however, relied upon for pushing the stem outward as that is done by the usual pendant-spring 14. The outward movement of 90 the stem 6 is limited by the engagement of the pinion 13 with the stem-winding pinion 15 through which the stem 6 passes and with 95 which it is coupled for rotation. The said pinion 15 bears upon the inner end of the pendant 7 and meshes into the intermediate winding wheel 16 which in turn meshes into the winding wheel, which is not shown as this present invention is not concerned with the stem-winding mechanism. The front 100 movement plate 5 is formed with a clearance notch 17 for the reception and play of the pinion 15. The ring 18 partly covering the plate 8 forms a portion of the watch case which, however, has nothing to do with 105 my present invention.

I claim:—

1. In a stem-winding and stem-setting watch, the combination with a dial-wheel, of a radially movable stem-setting wheel, a 110

longitudinally movable and rotatable stem, a stem-setting pinion carried thereby, and means for maintaining the stem-setting wheel in constant mesh with the stem-setting pinion and demeshed from the dial-wheel.

2. In a stem-setting and stem-winding watch, the combination with a dial-wheel, of a radially movable stem-setting wheel, a stud therefor a washer fixed upon the inner end of the said stud, a longitudinally movable and rotatable stem, a stem-setting pinion carried thereby and intermeshed with

the teeth of the stem-setting wheel, and a spring engaged with the said washer for normally maintaining the stem-setting wheel demeshed from the dial-wheel and in engagement with the stem-setting pinion.

In testimony whereof, I have signed this specification in the presence of two subscribing witnesses.

WILSON E. PORTER
